UNITED STATES PATENT OFFICE.

SARA SCOTTER, OF HOVE, BRIGHTON, ENGLAND.

FIRE-ESCAPE.

No. 838,555.

Specification of Letters Patent.

Patented Oct. 16, 1906.

Application filed March 22, 1905. Serial No. 251,367.

To all whom it may concern:

Be it known that I, SARA SCOTTER, a subject of the King of Great Britain, residing at 14 Brunswick Place, Hove, Brighton, in the county of Sussex, England, have invented certain new and useful Improvements in Fire-Escapes, of which the following is a specification.

The improvements relate to a fire-escape apparatus inclosed in a chest of suitable design to stand before a window or other opening in any building.

The complete details of the apparatus are as follows: The chest containing this escape is made of strongly-framed wood or of iron or other metal and is mounted on casters, so that it can be readily moved from place to place. The top cover is made in two hinged leaves which fold back and is made to suit the width of any window or other opening. The half of the hinged cover adjoining the window when folded back rests upon the bottom of the window-frame, thus forming a saddle. On the under side of this saddle are two rollers, upon which the escape-ladder runs. The ladder itself is flexible. At the bottom of this ladder is a collapsible cradle of fire-proofed canvas, to which are attached guide-ropes, which, as an additional precaution, may be held by any one in the street to help to guide the ladder in its first descent. The ladder winds upon a roller or drum fitted inside the chest, which is worked by means of toothed gearing attached to a crank or handle at one side of the chest. When the whole of the ladder is wound over the drum, the cradle folds over and rests upon the ladder at the top of the chest, just inside the cover. There is also a second roller or drum inside the chest, smaller than the first, but similarly worked by gearing, and an outside handle, round which are wound two steel or other ropes, attached to a second collapsible fireproofed canvas cradle. On one side of this second cradle are fixed two rollers, which allow it to be quickly run down the face of the ladder and quickly raised at will for fresh service.

The chest contains all the necessary fittings, (drums, gearing, ladder, cradles, ropes, &c.,) so that when the cover is shut it forms a very compact piece of furniture.

Referring to the accompanying drawings, Figure 1 is a plan showing the chest in front

of a window. Fig. 2 is a side view. Fig. 3 is a front view. Fig. 4 is a side view of cradle No. 2, showing the rollers which run along the face of the ladder and also showing the guide-ropes. Fig. 5 is a view of the chest with its wall broken away. Fig. 6 is a perspective view showing the application of the device to a window-frame.

A is the chest, containing one large drum B, upon which is wound the escape-ladder, and also a smaller drum C, upon which are wound the two steel ropes attached to cradle No. 2. The drums are worked by toothed gearing attached to handles on the outside of the chest.

D is the ladder, of steel wire.

E is cradle No. 1, which is collapsible and attached to the end of the ladder. Attached to E are guide-ropes.

F are small rollers on the under side of one half of the hinged cover to the chest, over which the escape-ladder runs.

G is the part of the hinged cover to which the rollers F are fixed. This part when opened back rests upon the bottom of the window-frame. It is previously referred to as the "saddle." H is the other or second part or half of the opening cover, hung upon strong hinges and adapted to fold back over the front of the chest.

I is the handle or crank for working the large drum B, attached to toothed gearing.

J is the handle for working the smaller drum C, attached to gearing similarly to I.

K are casters upon which the chest may be run.

L are the outside hinges to the part H of the divided cover. A similar pair would be fixed to the part G.

M is cradle No. 2, which is also collapsible and attached to two steel ropes N, working over the drum C. This cradle slides down the face of the ladder D by means of two small rollers O on one side.

P are two small props on the under side of cradle No. 2.

R is the bottom part of the window-frame, upon which the part G of the cover rests when folded back.

S is the window-sill.

T is the outer wall of a building.

U is the floor.

V is the ceiling.

W is the window.

X is one of the guide-ropes to cradle No. 1.

Y Y are the toothed or cog wheels or gearing attached to the drums and the outside cranks or handles.

5 What I claim, and desire to secure by Letters Patent of the United States, is—

1. A fire-escape comprising a receptacle with a hinged top in sections, one of which is constructed to form a saddle to engage over a window-sill, a drum in said receptacle, a second drum in said receptacle, a flexible ladder wound on the first-named drum, a rope wound on the other drum, and a cradle carried by said rope and adapted to slide on said ladder.

15 2. A fire-escape comprising a receptacle with a hinged top in sections, one of which is constructed to form a saddle to engage over a window-sill, a drum in said receptacle, a second drum in said receptacle, a flexible ladder wound on the first-named drum, a rope

wound on the other drum, and a cradle carried by said rope adapted to slide on said ladder and rollers on said saddle.

3. A fire-escape comprising a receptacle with a hinged top in sections, one of which is constructed to form a saddle to engage over a window-sill, a drum in said receptacle, a second drum in said receptacle, a flexible ladder wound on the first-named drum, a rope wound on the other drum, and a cradle carried by said rope adapted to slide on said ladder, rollers on said saddle and a collapsible cradle carried by said ladder.

30 In testimony whereof I have hereunto set my hand, in presence of two subscribing witnesses, this 6th day of March, 1905.

SARA SCOTTER.
